[57] ABSTRACT

A closed loop transport system comprises an articulated belt mounted on a support body and forming a closed loop around the body. An air bearing is disposed between the support body and the underside of the belt, the air bearing being fed with pressurized air from within the support body through apertures in the support body on the surface over which the belt passes. The air bearing has continuous sprung edge seals at each side of the belt that have one end attached to the belt and the other end bearing on a complementary contact strip on the support body thereby to provide a low friction continuous contact which reduces escape of air from the bearing.

TRANSPORT SYSTEMS

This invention relates to transport systems.

According to the present invention there is provided a closed loop transport system, comprising a rigid or semi-rigid articulated belt mounted on a support body and forming a closed loop around said body, wherein said belt is supported on said body by an air bearing intermediate said belt and said support body, said bearing being supplied with pressurised air from within said support body through apertures in said support body on the surface over which the belt passes.

Embodiments of the present invention will now be described, by way of example, with reference to the accompanying drawings, in which:

FIG. 1(a) illustrates the basic operation of a first type of closed loop system according to the present invention having a continuous horizontal loop.

FIG. 1(b) illustrates the basic operation of a second type of closed loop system according to the present invention having a continuous vertical loop.

FIG. 2(a) shows a method of maintaining pressurised air within the support body along the length of the body in a first embodiment of the first type of closed loop system.

FIG. 2(b) shows the use of a self-centering carrier platform in the first type of closed loop system.

FIG. 2(c) shows the use of a guided carrier platform in the first type of closed loop system.

FIG. 2(d) is a detail of the edge seal used in the first type of closed loop system.

FIG. 2(e) is a sectional elevation of the second type of closed loop system taken along the line 2b—2b in FIG. 2(f).

FIG. 2(f) is a sectional elevation of FIG. 2(e) taken along the line 2a—2a.

FIG. 2(g) is a detail of the edge seal used in FIGS. 2(e) and 2(f).

FIG. 3(a) is a cross-sectional view of a first embodiment of the first type of closed loop system.

FIG. 2(b) is an elevation of the embodiment shown in FIG. 3(a).

FIG. 4(a) is a cross-sectional view of a second embodiment of the first type of closed loop system.

FIG. 3(b) is an elevation of the embodiment shown in FIG. 4(a).

FIG. 5(a) is a small scale elevation of the embodiment shown in FIGS. 3(a) and 3(b).

FIG. 5(b) is a small scale elevation of the embodiment shown in FIGS. 4(a) and 4(b).

FIG. 6(a) and 6(b) are the plan and elevation of an access station for use with the first and second embodiments of the first type of closed loop system for enabling the access and egress of passengers to the containers.

FIG. 6(c) is a first embodiment of the second type of transfer system for use in the access station shown in FIGS. 6(a) and 6(b).

FIG. 6(d) is a detailed sectional elevation of the belt in FIG. 6(c) taken along the longitudinal length of the belt.

FIG. 6(e) is a cross-sectional elevation of the belt in FIG. 6(c) along the line 6c—6c.

FIG. 6(f) is a detail of the area B in FIG. 6(e).

FIG. 7(a), FIG. 7(b) and FIG. 7(c) is the plan, elevation and cross-sectional elevation of an access station

which utilises the variable speed access belt described in FIG. 6(c), FIG. 6(d), FIG. 6(e), and FIG. 6(f).

FIG. 7(d) is a cross-sectional elevation of a vertically stacked access station.

FIG. 8 is a plan view of a variable speed transfer loop cooperating with a non-stop express transfer loop, which loops utilise both the first and second type of closed loop systems according to the present invention.

FIG. 9 illustrates the possibility of transferring many classes of goods on a closed loop system of the type shown in FIGS. 4(a), 4(b) and 5(b).

FIG. 10 illustrates a moving "side walk" according to the present invention.

FIG. 11 is a platform loop network of an access station having vehicle and pedestrian access to the station.

FIG. 12 is a cross-section along the line 12a—12a in FIG. 11.

FIG. 13 is a cross-section along the line 13b—13b in FIG. 11.

FIG. 14 is a closed loop system of the first type and has an access station having a closed loop system of the second type.

FIG. 15 is a plan of a number of continuous non-stop loops cooperating with each other.

FIG. 16(a) is a medium range operational loop showing several types of two stage access station layouts.

FIGS. 16(b), and (c) illustrate the intermodule transferability of containers with transport loops according to the present invention.

FIG. 17(a) and FIG. 7(b) illustrate further combinations of transfer loops to form passenger and freight transport systems.

FIG. 18 is a graphic illustration of the closed loop system shown in FIG. 9.

FIG. 19 is a graphic illustration of the embodiment shown in FIGS. 3(a) and 3(b).

FIG. 20(a) is an elevation of modules for use on high speed closed loops.

FIG. 20(b) is an elevation of a container module for use with high speed closed loops.

FIG. 21(a) is a high speed closed loop network.

FIG. 21(b) is a three stage station loop module transfer.

FIG. 21(c) is a three stage station loop for gaining access to a high speed closed loop network.

FIG. 22 is a first embodiment of a third type of closed loop system according to the present invention.

FIG. 23 is a sectional elevation of FIG. 22 along the line 23a—23a.

FIG. 24 is a second embodiment of a third type of closed loop system according to the present invention.

FIG. 25 is a sectional elevation of FIG. 24 along the line 25a—25a.

FIG. 26(a) is a sea to land transfer system which utilises a closed loop of the second type according to the present invention.

FIG. 26(b) is a two-way system closed loop transfer which utilised the second type of closed loop for enabling the transfer of containers to and from vehicle based transfer platforms.

FIG. 26(c) illustrates the use of the third type of closed loop system according to the present invention to drive a vehicle.

FIG. 27 is an application of a transfer loop of the type shown in FIGS. 22 to 25 to power an amphibious vehicle.

FIG. 28 shows the operation of the vehicle in FIG. 27 when in water.

In FIG. 1(a) a continuous belt 1 having an edge seal 2 runs in a horizontal loop on a support body 3.

The belt 1 is supported on the body 3 by an air bearing 4 formed by the belt 1, the edge seals 2 and the surface of the support body, the bearing being supplied with pressurised air 5 from within the support body 3 through apertures in the support body 3.

In FIG. 1(b) the arrangement is similar to that in FIG. 1e except that the belt 1 moves only in a vertical loop.

In FIG. 2(a), a carrier platform 7 is supported on a duct beam 8 by a guidance pressure chamber 9 which is supplied through apertures in the beam 8 with pressurised air from within the duct beam 8. The pressurized air is supplied to the duct beam 8 by air pumping stations 10 arranged at uniform intervals along the length of the beam 8.

In FIG. 2(b) the carrier platform 7 is supported on two parallel duct beams 8 whose upper surfaces are angled towards each other in order to accommodate the v-shaped lower surface of the carrier platform 7. The platform 7 is supported by pressure chambers 9 intermediate the lower surfaces of the carrier platform 7 and the duct beams 8. The pressure chambers 9 are supplied with pressurised air from within the duct beams 8 through apertures 11 in the angled surfaces of the duct beams 8. The duct beams 8 also have bracing members 12 for strength. The carrier platform 7 is driven by a linear induction motor 13 which depends from the carrier platform 7 on a suspension diaphragm 14 and cooperates with a rail 15 located intermediate the parallel duct beams 8 and which is protected by a cover-plate 16.

In FIG. 2(c), a carrier platform 7, is supported on two parallel duct beams 8 and is guided along said beams 8 by two guide members 17 depending from the lower surface of the carrier platform 7 intermediate the two duct beams 8. The platform 7 is supported on the upper surfaces of the duct beams 8 by pressure chambers 9 and similarly the guide members 17 contact the adjacent sides of the duct beams 8 through pressure chambers 18. Pressurised air is supplied to the pressure chambers 9 through apertures 11 and to pressure chambers 18 through apertures 19. The duct beams 8 have bracing members 20 for strength. The carrier platform 7 is again driven by a linear induction motor 13 which depends from the carrier platform 7 on a suspension diaphragm 14, and co-operates with a rail 15 located intermediate the parallel duct beams 8, and which is protected by a cover-plate 16.

In FIG. 2(d), the edge seal which closes the ends of the pressure chambers 9 and 18 comprises a continuous spring 21 have one end attached to the edge of the lower surface of the carrier platform 7 and the other end bearing upon a contact strip 22 located along the edge of the upper surface of the duct beam 8. A protective cover 23 is also provided which is attached to the carrier platform and depends over the spring to below the edge of the duct beam 8.

In FIGS. 2(e) and 2(f), a continuous carrier belt 30 is supported on a support duct 31 by a support pressure chamber 32, the upper portion of which is supplied by pressurised air from within the main portion of the duct 31 through apertures 33, and the lower portion of which is subjected to a suction force through apertures 34 communicating with a lower portion of the duct 31

which is used to provide said suction force. The high and low pressure areas of the support pressure chamber 32 are separated from each other by gates 35.

In FIG. 2(g), the edge seal which closes the ends of the pressure chamber 32 comprises a continuous spring 36 having one end attached to the continuous carrier belt 30 and the other end bearing against the edge of the support duct 31, said edge having a ridge 37 for guiding said belt 30 and to prevent lateral movement of said belt 30.

In FIGS. 3(a) and (b) and FIG. 5(a), a series of modular containers 40, coupled together by an articulated coupling 41 and mounted on a track comprising two parallel ducts 42, spaced apart and which are mounted on support members 43 at regular intervals along the length of the track. The containers 40 are supported vertically on the track by air bearings in the form of support chambers 44 intermediate the lower surfaces of the containers 40 and the upper surfaces of the ducts 42, and are supported laterally by similar air bearings in the form of support chambers 45 intermediate the opposing sides of the ducts 42 and vertically depending flanges 46 of the container 40.

The support chambers 44 and 45 comprise an outer membrane 47 having semi-rigid diaphragm edge seals 48 which bear against contact strips 49, attached to the ducts 42, and an inner membrane 50 which is telescopic to accommodate a speed variation of the containers 40. Pressurized air is supplied to the support chambers 44 and 45 from the ducts 42 through a plurality of apertures 51 and 52. The pressure is maintained by regularly spaced fan stations. The temperature of the pressurized air may be controlled and the containers 40 may be adapted so that air from the ducts 42 may enter the container 40, thus providing heating in the winter.

The motive and braking power for the closed loop of containers 40 is provided by linear induction motors 53 cooperating with a rail 54 located between the ducts 42 on a mounting bracket 55. The motors 53 are suspended from the containers 40 on supports 56 and are spaced at intervals around the loop.

The containers 40 have seating accommodation 57 and access to the containers 40 is gained through the sides, the upper panel 58 being vertically retractable and the lower panel 59 being a panel which retracts round a roller 60.

A power rail 61 is also provided for supplying power to the motors 53 and for lighting and the ducts 42 are strengthened by bracing members 62.

This system is designed primarily as a non-stop transport system in which passengers would enter and exit the containers at special access stations by means of variable speed transfer belts 63 which are described later on.

In FIGS. 4(a) and (b) and FIG. 5(b), modular containers 40 are carried on platforms 60 which are interconnected by couplings to form a closed loop. The platforms 60 are supported on a track in the same manner as used for the containers 40 in the first embodiment shown in FIGS. 3(a) and (b). The containers 40 are held in position on the platforms 60 by guide and locking members 62. Intermediate the containers 40 and the platforms 60 a lateral transfer surface 63 is provided for enabling the containers to be removed from the closed loop at suitable access points on the loop. Normally two loops of containers 40 run side by side in

opposite directions and are synchronised to each other by means of a synchronising chain 64 which run on idler wheels 65. In this embodiment the duct beams 42 are supported on foundation tie beams 66 which rest on pneumatic foundation bags 67. The containers 40 can therefore be transferred from the platforms 60 in a simple manner. This embodiment is designed as a non-stop transport system in which passengers enter and exit the containers at special access stations and also freight is carried in special containers on the platforms 60.

In FIGS. 6(a) and (b), a continuous non-stop transfer belt 70, running parallel with the continuous flow of containers 40 for a predetermined length, is provided to permit passengers to enter or exit the containers 40. The belt 70 is designed to accelerate passengers from 3 m.p.h. to 20 m.p.h., the speed at which the containers are traveling, and the belt being longitudinally extensible in order to facilitate the speed variation.

When passengers are travelling on the belt at 20 m.p.h. there will be no relative movement between the belt 70 and the containers 40. At this point the sides of the container 40 will open as hereinbefore described and passengers will then enter or exit the containers 40.

In FIGS. 6(c), (d), (e) and (f), the belt 70 runs on a vertical closed loop system as described in FIGS. 2(e), (f), and (g). The belt 70 comprises a plurality of elements 71 laterally spaced apart but slidably connected to each other such that said elements 71 may move longitudinally with respect to each other to thereby allow the belt 70 to telescope out or in depending upon the speed of the various vertical closed loop systems over which the belt passes. The belt 70 is also capable of self cleaning as waste on the surface elements 71 will pass through the spaces in the elements on to the lower belt surface 30 of the vertical closed loop system 72. At the end of each loop 72 the waste material will drop on to waste collection chutes 73 from which the waste can be easily removed.

In FIGS. 7(a), (b) and (c), two continuous flows of containers 40 in opposite directions pass through an access station 74. Passengers wishing to enter the containers step on to the entry point 75 of the variable speed belt 70. They are then accelerated from approximately 3 m.p.h. to the speed of the containers (20 m.p.h.) at which point they will then be travelling parallel with the containers. As the speed of the passengers and the containers 40 are the same, the passengers may simply walk on to the containers.

In FIG. 7(d) an alternative arrangement is to that shown in FIGS. 7(a), (b) and (c) has the two continuous flows of containers 40 travelling in opposite directions one below the other and the access station is vertically stacked to allow access and egress of passengers to the containers.

In FIG. 8, a non-stop loop 76, containers 40 travelling at speeds exceeding 40 m.p.h. is shown. Access to this loop is attained by a transfer belt 77 to transfer passengers initially on to a first variable speed closed loop 78 of containers 40 travelling at 40 m.p.h. when passing the transfer belt 77. The passengers in this first loop 78 are then accelerated to the same speed as the containers 40 on the second closed loop 76 at which point they transfer from one loop of containers to the other. This method enables passengers to transfer on to high speed loops of containers. To enable freight etcetera to be processed and transferred to the express loop 76, a further loop 79 (only part is shown) is arranged for access

to the first loop 78. This loop 78 has several branch access points 79 for loading and unloading freight.

In FIG. 9, a closed loop system 80 has a number of containers 40 spaced at intervals along its length. A vehicular access station 81 is provided to enable private urban modules 82, conventional automobiles 83, bus type vehicles 83 and trucks 84, to gain access to the loop 80. A further access station 86 is provided for allowing, for example, private companies to transfer their own private containers 87. These containers 87 may be stored in private storage depots 88 beside the loop 80 or may be collected and transported to depots at a distance from the loop 80. Also, pedestrian access stations 89 may be provided to allow pedestrians access to the stationary containers 40 on the loop 80.

In FIG. 10 a moving sidewalk comprises a moving loop surface 90, supported by pressurised air from within duct beams 91, and is powered by linear motors 92 depending from the moving surface 90 between the duct beams 91 and spaced at regular intervals along the moving surface. The support for the moving surface is of the type described in FIG. 2(c). In this embodiment the whole unit is located in a recess 93 in the ground, but it may also be elevated above ground if desired.

In FIG. 11, the loop 94, has a vehicle access area 95 for vehicles 96 and a passenger access area 97.

In FIG. 12 at the vehicle access points the cars 96 may be driven on to the loop 94 from an accelerator belt 97. The area in which cars 96 may be driven on to the loop 94 is interspersed with container 40 for carrying passengers. The loop as described hereinbefore is supported on twin duct beams 98. A mobile barrier 99 is also provided to prevent any vehicles driving off the edge of the loop 94.

In FIG. 13, passengers are transferred to the loop 94 by an access belt 100 which accelerates the passengers from walking pace to the speed of the containers 40 on the loop 94. An air curtain 101 is also provided at the edge of the passenger access belt 100 to protect passengers from the weather.

In FIG. 14, a transfer loop 102 of the type described in FIG. 2(c) having twin duct beams 103, has an access station 104 including laterally movable surface elements 105 mounted on a closed loop system of the type described in FIGS. 2(e) and (f), which has a support surface 106, a pneumatic bearing 107 and a core 108.

In FIG. 15, loops of various sizes and speeds are interconnected at inter loop transfer points 110 and each loop has a number of access stations, both side by side stations 111 and vertically stacked stations 112.

In FIG. 16(a) the operational loop 111 is of the constant velocity type. The loop 111 has two end loop access stations 112 which intermediate variable speed loops 113 and freight handling loops 114. The loop also has two types of intermediate access stations 115 and 120.

The first type of intermediate access station 115 includes two variable speed loops 116 which cooperate with opposite sides of the loop 111, and freight handling loops 117, and a passenger access station 118 to allow passengers access to the intermediate loops 116 and hence the main loop 111.

The second type of access station 120 includes two variable speed intermediate loops 121 which cooperate with the main loop 111 at a point where both sides of the loop 111 are vertically stacked. The intermediate

loops 121 also cooperate with freight handling loops 122 and passenger access stations 123.

In FIG. 16(b), containers 40 are transported by a special adapted vehicle 125 to an access station 126 where the containers 10 are moved laterally from the vehicle 25 on to a variable speed transfer belt 127 which accelerates the containers 40 to the speed of a closed loop transfer system 128 at which point the containers 40 are moved laterally on to the closed loop system 128 for further transportation.

In FIG. 16(c), containers 40 are removed from an aircraft 129 on a handling vehicle 130 adapted for use with aircraft. The vehicle 130 has a loading platform 131 which can be raised or lowered to any height depending on the aircraft 129. The vehicle then transports the containers 40 to an access station 132 where the containers are transferred firstly to a processing platform 133 and then on to a variable speed transfer belt 134. The belt 134 accelerates the containers 40 to a suitable speed for transferring to a constant speed closed loop 136 on which the containers 40 are transported to a terminal facility 137 for processing.

In FIG. 17(a) the transport loops 140, 141, 142 and 143 all meet at a point to and are arranged that passengers may change loops at this point and hence change their direction of travel.

In FIG. 17(b) two express loops 144 and 145 travelling at 80 m.p.h. communicate with each other at a point 146. An urban loop 147 travelling at 40 m.p.h. communicates with the express loop 145.

In FIG. 20(a), the module 150 for carrying a number of containers 40 for passengers and a module 151 for carrying only a single container 40 for passengers have aerodynamic nose and tail sections 152 and 153 respectively.

In FIG. 20(b), a module 154 for transporting a number of containers 40 at high speed has aerodynamic nose and tail sections 155. The containers 40 are transferable from the module 154. A pumping station 156 having an air intake 157 is shown which supplies pressurized air to the ducts 158. The containers 40 travel on carrier platforms 159 and joined to each other and to the nose and tail sections 155 by a pneumatic coupling 160.

In FIG. 21(a), a high speed network comprises three high speed loops 161, 162, 163 which communicate with each other at points 164, and 165. A typical station loop is shown at 166.

In FIG. 21(b) modules 167 can be gradually transferred from high speed loops by variable speed belts 168, 169 and 170.

In FIG. 21(c), access to a high speed loop 171 by a three station loop transfer. The first transfer occurs at a station 172 at which a passenger steps on to a moving belt which will accelerate him to a speed of 150 m.p.h. on a first loop 173. At a second station 174, the passenger can transfer to a second loop 175 which will accelerate him from 150 to 300 m.p.h. At a third station 176 the passenger is then travelling at the same speed as the high speed loop 171 and can therefore transfer to the loop 171.

In FIGS. 22 and 23, a flexible rubber tread 200 is supported on support core 201 by a plurality of support pressure chambers 202 intermediate the tread 200 and the support core 201. Pressurised air is supplied to the support chambers 202 through an air supply duct 203, a pressurized air supply chamber 204 and a plurality of

apertures in the support core 201. The tread is also guided on the lower portion of the support core 201 by tread support webs 205 protruding from the inside surface of the tread 200 and engaging channels 206 in the lower surface of the support core 201. The webs 205 are guided along the channels 206 by guidance pressure chambers 207 which are supplied through apertures in the channels 206 with pressurised air from the supply pressure chamber 204. The outer support pressure chambers 202 are pressure chambers 208 are isolated from the guide pressure chambers by internal edge seals 209. The webs 205 are covered by a flexible pressure skin 210. The whole unit is provided with a side bumper guard 211 and has steering joints 212 and is driven by a power wheel 213. Also, the support chamber 202 have end gates 214 to help maintain the pressure in the chambers which bear the weight of the whole unit.

In FIGS. 24 and 25, a flexible rubber tread 220 is supported on a support core 221 by a support pressure chamber 222 intermediate the tread 220 and the support core 221. Pressurized air is supplied to the pressure chamber 222 through an air supply duct 223 and a plurality of apertures 224 in the support core 221. The edges of the tread 220 are provided with continuous spring edge seals 225 which bear against a contact ship 226 and thereby seal the pressure chamber 222. The tread 220 is also provided with a guide runner 227 which engages a semi-rigid guide channel 228 which is supported on the lower section of the support core 221 by a pressure chamber 229 which is anchored to the support core 221 by anchor plates 234. Pressurised air is supplied to the pressure chamber 229 from the duct 223 through a valve 230. The support core 221 and tread 220 are provided with a bumper guard 231. The whole unit is provided with steering joints 232 and a power wheel 233 for driving the track 220 around the core 221 so that the unit may be used as a track for a vehicle.

In FIG. 26(a), a chain of containers 240 floating in a harbour 241 can be removed from the water and transferred to a suitable location 242 on land by use of a partly submerged transfer loop 243 of the second type according to the present invention.

In FIG. 26(b), containers (not shown) may be transferred to waiting vehicles 244 by using a plurality of transfer loops 245.

In FIG. 26(c) a transfer loop 246 of the type described in FIGS. 22 to 25 is used to power a vehicle 247.

In FIG. 27, a vehicle 250 for carrying standard containers 251 or specialised containers 252, is driven by a closed loop system 253 of the type described in FIGS. 22 to 25. The closed loops 253 are mounted on the vehicle 250 through a suspension medium 254 and pressurised air 256 is supplied to the closed loops from a power module 255 which also drive the power wheels (not shown) to rotate the closed loops 253. The closed loops 253 are also provided with buoyant cores to enable the vehicle to travel over water.

In FIG. 28, the vehicle 250, is shown travelling in water. The closed loops 253 provide an efficient driving force in the water due to the linear motion of the closed loops against the water and the resultant low hydrodynamic drag.

What I claim is:

1. A closed loop transport system comprising a support body having a duct formed therein, a rigid articulated belt disposed about said support body over said duct and forming a closed loop about said body, said belt comprising a plurality of individual load-supporting cooperatable segments which are relatively movable and which are constructed with a substantially air impervious material, each of said segments having an end margin which is opposed to an end margin of a next adjacent segment, connecting means interconnecting said segments for articulated movement relative to each other and in such manner that the end margin of one segment is opposed to the end margin of the next adjacent segment, said connecting means also providing a substantially air impervious construction between the end margins of each of two adjacent segments in the articulated belt, said belt being slightly spaced from said support body at least for portions of its length to form an air bearing space intermediate the underside of said belt and said support body, sealing means associated with said segments and which provides sealing contact along at least one side of the segments and the support body in the direction of movement thereof in such manner that the sealing contact and the air impervious construction of said connecting means provides a substantially air impervious seal to thereby maintain the air bearing space, and means forming a plurality of apertures in said support body on the surface over which said belt passes, said apertures being in communication with said air bearing space and the interior of support body for supplying pressurized air to the air bearing space from within the support body to generate an air bearing within the air bearing space, said belt being located on said support body and with respect to said duct so that the pressurized air which passes through said apertures into said air bearing generates the air bearing for supporting said belt about said support body during its movement about the support body.

2. A closed loop transport system according to claim 1, wherein said belt is driven by a plurality of linear induction motors depending from the underside of said belt between the ducts and cooperating with a rail mounted between said ducts.

3. A closed loop transport system according to claim 1, wherein said loop is a horizontally disposed loop and said belt is in the form of a closed loop of interconnected container modules.

4. A closed loop transport system according to claim 1, wherein said loop is a horizontally disposed loop and said belt is in the form of a closed loop of interconnected transport platforms on which container modules may be transported.

5. A closed loop transport system according to claim 1, wherein said belt travels at a constant speed around the loop.

6. A closed loop transport system according to claim 1, wherein said belt travels at a variable speed around said loop.

7. A closed loop transport system according to claim 1, wherein access stations are provided for access and egress to said closed loop, said access stations include a variable speed belt on which loads are accelerated from a low speed to the speed of said closed loops, said variable speed belt running parallel with said closed loop at the same speed as the closed loop over a suit-

able distance to allow loads to be transferred on to said closed loop.

8. A closed loop transport system according to claim 1, wherein two closed loops travelling in opposite directions are positioned side by side and access stations are positioned side by side said closed loops.

9. A closed loop transport system according to claim 1, wherein two closed loops travelling in opposite directions are stacked vertically one upon the other and access stations are also stacked vertically one upon the other.

10. A closed loop transport system according to claim 1, wherein smaller low speed loops are used to transfer loads on said smaller low speed loops to larger high speed loops.

11. A closed loop transport system according to claim 1, wherein said belt comprises a plurality of laterally spaced telescoping segments to allow said belt to travel at varying speeds over said closed loop.

20 12. A closed loop transport system according to claim 1, wherein said belt is a rubber tread which has a plurality of support webs projecting into said air bearing and at least part of said support body has a plurality of guide channels to accommodate said support webs and thereby guide said webs, a power wheel mounted on said body and engageable with said tread for driving said tread around said support body.

13. A closed loop transport system according to claim 1, wherein said belt is a rubber tread which has a plurality of guide runners projecting inwardly from the centre of said tread, which engage a semi-rigid guide channel mounted around at least part of said support body such that said tread is guided around said support body, a power wheel mounted on said support body and engageable with said tread for driving said tread about said support body.

30 14. A closed loop transport system characterized by a rigid articulated belt mounted on a support body and forming a closed loop around said body wherein said belt is supported on said body by an air bearing intermediate the underside of said belt and said support body, said bearing being supplied with pressurised air from within said support body through apertures in said support body on the surface over which the belt passes, said air bearing having continuous sprung edge seals at each side of said belt with one end attached to said belt and the other end bearing upon a complementary contact strip on said support body thereby to produce a low friction continuous contact which reduces the escape of air from said air bearing.

40 15. A closed loop transport system according to claim 14, wherein said loop is a horizontally disposed loop.

50 16. A closed loop transport system according to claim 15, wherein said support body comprises two parallel spaced ducts, said ducts having upper surfaces which are inclined to each other and the lower surface of said belt is V-shaped such that said belt is centred between said ducts and supported thereon by two continuous air bearings formed by air bearing spaces intermediate the belt and the ducts, and which air bearings are supplied with pressurised air from within said ducts through a plurality of apertures on the upper surfaces of said ducts.

60 17. A closed loop transport system according to claim 15, wherein said support body comprises two rectangular parallel spaced ducts and said belt is sup-

ported on said ducts by air bearings formed by air bearing spaced intermediate the lower surface of the belt and the upper surfaces of the ducts, said belt also being guided along said ducts by further air bearings intermediate the opposing sides of said ducts, and guide members depending from the underside of said belt between said ducts, said air bearings being supplied with pressurised air from within said ducts through a plurality of apertures in said ducts.

18. A closed loop transport system according to claim 15, wherein said belt travels at a variable speed around said loop.

19. A closed loop transport system according to claim 18, wherein said belt comprises a plurality of laterally spaced telescoping segments to allow said belt to travel at varying speeds over said closed loop.

20. A closed loop transport system according to claim 1, wherein said loop is a vertically disposed loop.

21. A closed loop transport system according to claim 20, wherein said belt is a rubber tread which has a plurality of support webs projecting into said air bearing and at least part of said support body has a plurality of guide channels to accommodate said support webs and thereby guide said webs, and therefore the tread along said guide channels by means of further air bearings intermediate the walls of said channels and the sides of said webs, a power wheel mounted on said support body, and engageable with said tread for driving said tread around said support body.

22. A closed loop transport system according to claim 20, wherein said belt is a rubber tread which has a plurality of guide runners projecting inwardly from the centre of said tread, which engage a semi-rigid guide channel mounted around at least part of said support body such that said tread is guided around said support body, a power wheel mounted on said support body and engageable with said tread for driving said tread around said support body.

23. A closed loop transport system comprising a support body, a rigid articulated belt disposed about said support body and forming a closed loop about said body, said belt being slightly spaced from said support body at least for portions of its length to form an air bearing space intermediate the underside of said belt and said support body, means forming a plurality of apertures in said support body on the surface over which said belt passes and which apertures are in communication with said air bearing space so that pressurised air introduced with respect to said support body passes through said apertures into said air bearing space to form an air bearing support for said belt, a sprung edge seal operatively associated with each of the opposite longitudinal ends of said belt and said support body and each said seal bearing against a complementary contact strip in sliding continuous contact therewith to produce a low friction continuous contact which reduces escape of air from said air bearing space.

24. A closed loop transport system according to claim 23, wherein a sprung edge seal is operatively attached to each of the opposite longitudinal ends of said belt, and said complementary contact strips are located

on the opposite sides of said support body so that the free ends of the respective ones of said seals are in sliding continuous contact with said contact strips.

25. A closed loop transport system comprising a support body having a centrally located V-shaped duct formed by a pair of upper surfaces which are inclined to each other, a rigid articulated V-shaped belt disposed about said support body and forming a closed loop about said body, said belt comprising a plurality of individual load-supporting cooperatable segments which are relatively movable, means interconnecting said segments for articulated movement relative to each other, said belt being slightly spaced from said support body at least for portions of its length to form an air bearing space intermediate the underside of said belt and said support body, said segments being connected in such manner as to be substantially air impermeable to thereby maintain the air bearing space between said belt and V-shaped duct, and means forming a plurality of apertures in said duct on the surface over which said belt passes, said apertures being in communication with said air bearing space and the interior of said support body for supplying pressurized air to the air bearing space from within the support body to generate an air bearing within the air bearing space, said belt being substantially centered within the upper surface of said V-shaped duct so that the pressurized air which passes through said apertures into said air bearing space generates the air bearing for supporting said belt during its movement about the support body.

26. A closed loop transport system comprising a support body including at least two parallel spaced ducts and each of said ducts having upper surfaces, a rigid articulated belt disposed about said support body and forming a closed loop about said body, said belt comprising a plurality of individual load-supporting cooperatable segments which are relatively movable, means interconnecting said segments for articulated movement relative to each other, said belt being slightly spaced from said support body at least for portions of its length to form air bearing spaces intermediate the underside of said belt and the upper surfaces of the spaced ducts in said support body, said segments being connected in such manner as to be substantially air impermeable to thereby maintain the air bearing spaces between said belt and said spaced ducts, means forming a plurality of apertures in each of said ducts on the surface over which said belt passes, said apertures being in communication with said air bearing spaces and the interior of said support body for supplying pressurized air to each of the air bearing spaces from within the support body to generate air bearings within each of the air bearing spaces, said belt also being guided along said ducts by further air bearings intermediate the opposing sides of said ducts, and guide members depending from the underside of said belt between said ducts so that the pressurized air which passes through said apertures into said air bearing spaces generates the air bearings for supporting said belt during its movement about the support body.
